(57) **CLAIM**

The ornamental design for a decorative wheel cover as shown and described.

DESCRIPTION

FIG. 1 is a front perspective view of a decorative wheel cover embodying my new design in relation to an environmental wheel;

FIG. 2 is a front elevation view thereof;

FIG. 3 is a front and right-side perspective view thereof;

FIG. 4 is a side elevation view thereof, relative to the top-left corner in FIG. 2;

FIG. 5 is a left side elevation view thereof, relative to the bottom-left corner in FIG. 2;

FIG. 6 is a top plan view thereof, relative to the top-right corner in FIG. 2;

FIG. 7 is a side elevation view thereof, relative to the right side in FIG. 2;

FIG. 8 is a side elevation view thereof, relative to the left side in FIG. 2; and,

FIG. 9 is a side elevation view thereof, relative to the bottom-left side in FIG. 2.

The broken line showing of an automotive rim are provided for the purposes of illustrating environmental structure and form no part of the claimed design.
